UNITED STATES PATENT OFFICE.

OAKLEY H. WARNE, OF ELBURN, ILLINOIS.

RAILROAD SPIKE.

Application filed June 5, 1925. Serial No. 35,030.

My invention relates to railroad spikes.

The ordinary form of railroad spike has a wedge-shaped end formed by two beveled faces meeting in an edge. This spike, I have discovered, possesses serious objections. In the first place, it is difficult to start the penetration of the spike in the hard wood, usually oak, employed for railroad ties, with the result that upon the first blow of the sledge, the spike is often dislodged and, flying off, frequently strikes the leg of the workman who is driving the same, with the consequences of scarred legs, torn clothes, and loss of time in replacing the spike. Secondly, the spike forces the fibers of the wood ahead of it and ruptures and separates and bends downwardly the fibers on either side of its passage, leaving the grain surrounding the wood in an open and jagged condition and forming an enlarged passage and spaces into which water can readily penetrate with the consequent rotting of the wood which in turn causes the loosening of the spike and a shorter life of the railroad tie.

It is the object of the present invention to overcome objections existing to the use of the present form of spike, and producing as has been discovered, the shortening of the life of the tie. The particular purpose of my invention is to obtain an easy initial penetrating action, and a clean shearing cut of the fibers, such as will permit the main body of the spike to follow the point without unduly bending and breaking the fibers and at the same time permit the proper "drawing" action of the spike toward the rail so that the spike head will be forced over the edge of the rail.

With these ends in view, my invention is embodied in preferable form in the spike hereinafter described and illustrated in the accompanying drawings, in which—

Fig. 1 is a side view in elevation looking toward the rear face of the spike, considering the face from which the head of the spike projects, as the front face;

Fig. 2, a similar view of one side of the spike;

Fig. 3, a similar view of the front face of the spike;

Fig. 4, a cross-section on line 4—4 of Fig. 2;

Fig. 5, a cross-section on line 5—5 of Fig. 2; and

Fig. 6, a cross-section on line 6—6 of Fig. 2.

Referring to the drawing, 1 indicates the main body portion of the spike which is of the standard rectangular form and standard dimensions, and 2 indicates the head which has the usual projecting flange or lip 3 adapted to take over the rail. The spike embodying my improvements is adapted to be made of the same quantity of stock as the standard spike, the reduced penetrating and cutting end being formed in the same forging operation by which the body of the spike is produced.

On the front face 4 of the spike or that face from which the projecting part 3 of the head extends, is formed a tapered portion 5, extending from a line at about three-fourths of the length of the spike from the head, to the lower end of the spike. This tapered part is preferably formed with a slight curvature. The function of this surface is to create a tipping or drawing action of the spike toward and against the rail so that the spike will pass toward the rail and the head lap over and grip the rail.

On the rear face of the spike, the latter is beveled or tapered off at each edge, from points beginning a considerable distance above the upper end of the tapered position 5, and continuing down to the end of the lower end of the spike. These beveled surfaces 6 widen gradually from their upper ends until they meet on the rear face of the spike in a common cutting edge 7. The edge 7 extends to the lower end of the spike and then joins the lower ends of the transversely inclined edges 8 which are formed by the junction of the lower edges of the beveled surfaces 6 with the front face 4. The meeting of the cutting edges 7 and 8, 8, forms an acute triangularly shaped penetrating point which will effectually penetrate the wood of the tie under the starting blow and yet will enter the wood without undue bending and lateral separation of the fibers. The cutting edge 7 is also curved or inclined from rear to front to increase the penetration action of the point.

It will be seen that the central cutting edge 7 is relatively long compared to the side edges 8, thus extending the tapered and more readily penetrative part of the spike toward the head for a considerable distance, which greatly assists in the penetration of

the wood, and without undue rupture of the fibers. This gradual tapering of the spike is further obtained by the extension of the beveled faces 6 to points considerably beyond the upper termination of the cutting edge 7.

5 The spike is adapted to be formed from stock of the same dimensions now employed for standard spikes and the cutting edges and tapers may be formed in the forging 10 operation for making the body of the spike.

With the above form of spike, the long beveled or tapered faces on the rear face of the spike give an effectual penetrating action, while at the time their cutting edges 15 give a shearing cut which prevents splitting and tearing of the grain of the wood as the spike is driven into the tie. The location of the beveled surfaces forming the cutting edges and tapering point, on the face of the 20 spike opposite to that face carrying the tapered surface 5, co-operates with the drawing action of the latter surface by increasing

to some extent the pressure toward the projecting head, owing to the wedge formation of the rear face, thus forcing the head 25 against the rail flange.

The above results and actions have been practically demonstrated and observed in 30 tests of the spike.

What I claim is:

A railroad spike having a head projected from one face thereof and having a lower tapered surface along said face lying in a single transverse plane, the opposite face of the spike having two beveled faces extending from points above the upper termination of said tapered surface, said beveled faces meeting at an exterior sharp edge, the edges of said first surface and of said other faces being tapered inward and meeting in a point 35 at the termination of the spike.

40 In testimony whereof I affix my signature.

OAKLEY H. WARNE.
